S. V. REEVES

FIRE POT AND SEDIMENT SEPARATOR FOR HOT WATER STOVES

Filed March 15, 1923

UNITED STATES PATENT OFFICE.

SAMUEL V. REEVES, OF HADDONFIELD, NEW JERSEY.

FIRE POT AND SEDIMENT SEPARATOR FOR HOT-WATER STOVES.

Application filed March 15, 1923. Serial No. 625,175.

To all whom it may concern:

Be it known that I, SAMUEL V. REEVES, a citizen of the United States, residing at Haddonfield, in the county of Camden and 55 State of New Jersey, have invented a new and useful Fire Pot and Sediment Separator for Hot-Water Stoves, of which the following is a specification.

Broadly considered my invention comprehends certain novel features which are those particularly hereinafter described and claimed, and which among others, embrace the following:—

The construction of a preheating chamber 15 in such collocation with a main chamber or water jacket and a separating chamber that in the process of separating the sediment from both the cold water and the hot water, the cold water will enter the preheating chamber, circulate completely around it almost to the point of its entry, then diverge from it outwardly and horizontally into an exterior or separating chamber then pass upwardly and inwardly into the lower part 25 of the main heating chamber and then upwardly to a discharge at its top after completely circulating around and becoming heated within said main chamber.

A further feature is that by reason of its 30 being located at the lowest point of the fire chamber the preheating chamber will possess the advantage of receiving the heat contained in and through the products of combustion, in addition to the heat incident to 35 a fresh fire or from the combustion of fuel that is the first to be consumed and the first to be displaced by ashes.

A further feature is that the passage or 40 flow of the heated water from the preheating chamber outwardly into the exterior or separating chamber to which, although itself a sediment receptacle, may be attached an exterior lower sediment receptacle at a point outside of the line of the main waterway or 45 circulating chambers, where the water when agitated by excessive heat will have the least effect upon the deposit of sediment which has been conveyed through the circulation of the water to said lower receptacle.

50 A further feature is the ready separation of mineral matter and iron rust from the water which the arrangement of the several chambers makes possible,—the gravitation

of the sediment being thereby more readily attained than would be possible if it came in 55 the direct line with the water when agitated by thermo-pressure.

A still further feature is such a collocation of the several chambers that through the medium of an additional outlet between the preheating chamber and the main heating chamber, the water after making a complete circuit of the preheating chamber can pass directly upward into the main heating chamber,—such passage being supplementary of the passage of the water into and through the separating chamber in its passage to the main heating chamber.

A special advantage of my invention resides in the fact that because the preheating chamber occupies the same space and place usual for an ash ring, the utilization of every particle of heat for raising the temperature of water before it enters the main heating chamber is made possible.

75 Other advantages inhering in my construction will be readily understood by those skilled in the art.

For the purpose of illustrating my invention, I have shown in the accompanying drawings a form of it which is at present preferred by me, since in practice it will give satisfactory and reliable results.

80 It is to be understood, however, that the various instrumentalities of which my invention consists can be variously arranged and organized and that my invention is not, therefore, limited to the precise arrangement and organization of these instrumentalities as herein shown and described.

85 In the drawings, Figure 1 represents a side elevation of a fire pot and sediment separator, embodying my invention.

90 Figure 2 represents a sectional elevation on the line 2—2 of Figure 1.

95 Figure 3 represents a plan on the line 3—3 of Figure 2.

100 Figure 4 represents a plan on the line 4—4 of Figure 2, and Figure 5 represents a fragmentary sectional detail of the preheating chamber, the exterior or separating chamber, the main heating chamber, and the fire chamber.

105 Similar numerals of reference indicate corresponding parts.

In the drawings, 1 designates a preferably

cylindric fire chamber or fire pot of any usual character and assumed to be superposed upon a grate.

5 Encompassing this fire chamber are two water chambers, the lower of which is a pre-heating chamber 2, and the upper a main heating chamber 3.

10 These two chambers are separated near the basal portion of the main heating chamber and at the upper portion of the preheating chamber by a horizontal partition 4, and through them both from top to bottom extends a separating vertical partition 5.

15 6 designates what I term a separating chamber, which may be of such general and relative dimensions as are illustrated in the drawings, which is separated from both the main heating chamber 3 and the preheating chamber 2 by a partition wall 7, and which 20 is also in communication with both of said chambers through certain passageways.

Thus an outlet 8 leads from the preheating chamber 2 into the lower or sediment portion 9 of the separating chamber 6, an 25 orifice 10 through an outward extension of the horizontal partition 4 leads from the sediment chamber 9 into the lower exterior portion of the separating chamber 6, and an inlet 11 leads through the partition wall 30 7 from said lower portion of said separating chamber 6 into the main heating chamber 3.

Thus, further, an orifice 17 leads directly from the preheating chamber into the main heating chamber.

35 35 An outlet pipe 12, see Figure 5, leads through the bottom of the sediment chamber 9 of the separating chamber 6 to which may, if desired, be attached a sediment trap 13, see the dotted lines in Figure 1. If desired, 40 however, the sediment chamber may be sealed by a plug 14, see Figures 1 and 2.

15 45 15 is a cold water inlet into the preheating chamber 2 and 16 a hot water outlet from the upper portion of the main heating chamber 3 through pipes to a storage tank, boiler or any other receiving device.

50 My invention is adapted to be employed with any desired or conventional type of water jacket or boilers regardless of shape or design and may be constructed with a sediment separator as an elemental part of the construction irrespective of the intended use of the hot water. While the sediment chamber, as illustrated, is an integral part 55 of the construction, in some cases this can be dispensed with and simply the preheating chamber of the lower water jacket either as an integral part of the water jacketed fire pot or as a separate water ring therefrom which communicates in any desired 60 manner with respect to the water jacket of the main fire pot.

Special attention is directed to the fact 65 that in the construction, as shown, the sediment receiving or separator chamber is ex-

terior of the main water jacket so that there is no interference with the heating of the water in the main water jacket. The sediment may be removed by removing the plug 14 or by opening the cock in the sediment 70 receiving trap 13.

It will now be apparent that I have devised a new and useful fire pot and sediment separator for hot water stoves which embodies the features of advantage enumerated 75 as desirable in the statement of the invention and the above description, and while I have, in the present instance, shown and described a preferred embodiment thereof which will give in practice satisfactory and reliable results, it is to be understood that this embodiment is susceptible of modification in various particulars without departing from the spirit or scope of the invention or sacrificing any of its advantages. 80

Having thus described my invention what I claim as new and desire to secure by Letters Patent, is:—

1. A device of the class described, which comprises in integral assemblage a fire chamber, a pre-heating chamber encompassing the lower part of the fire chamber, a main heating chamber arranged above said pre-heating chamber and encompassing the upper part of said fire chamber, a horizontal partition between the pre-heating chamber and the main heating chamber, there being a vertically disposed orifice connecting said chambers, a partition disposed vertically throughout both said pre-heating chamber, and said main heating chamber to completely and transversely obstruct said chambers, a vertically disposed rectangular casing extraneous to said pre-heating chamber and said main heating chamber and separated therefrom by a partition wall which wall is slightly inclined, said casing forming a separating chamber and a sediment chamber, an outlet from the pre-heating chamber to the sediment chamber, an inlet from the separating chamber to the main heating chamber, a passageway between said sediment and separating chambers and a sediment trap removably connected with said sediment chamber. 100 105 110 115

2. A device of the class described, which comprises an integral assemblage, a fire chamber, a pre-heating chamber encompassing the lower part of the fire chamber, a main heating chamber arranged above said pre-heating chamber and encompassing the upper part of said fire chamber, a horizontal partition between the pre-heating chamber and the main heating chamber said partition having an orifice connecting said chambers, a separating chamber and a sediment chamber, an inclined partition separating the pre-heating and main heating chambers from said separating and sediment chambers said separating and sediment chambers being ex- 120 125 130

traneous to said pre-heating and main heating chambers, there being an orifice connecting said pre-heating and sediment chambers, an orifice connecting said sediment and said separating chambers, and an orifice connecting separating and said main heating chambers, a horizontal partition having a passageway therethrough arranged between said separating and sediment chambers, and a sediment trap removably connected with ¹⁰ said sediment chamber.
